CLAIM

The ornamental design for a children's desk, as shown and described.

DESCRIPTION

FIG. 1 is a front, left side and top perspective view of a children's desk showing my new design in a closed configuration;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a front, right side and top perspective view thereof, showing the children's desk in an open configuration.

The broken lines in the drawings illustrate portions of the children's desk that form no part of the claimed design.

1 Claim, 5 Drawing Sheets(56)
